UNITED STATES PATENT OFFICE.

DUANE H. CHURCH, OF NEWTON, MASSACHUSETTS.

STAKING-MACHINE.

SPECIFICATION forming part of Letters Patent No. 553,221, dated January 14, 1896.

Application filed July 20, 1895. Serial No. 556,559. (No model.)

To all whom it may concern:

Be it known that I, DUANE H. CHURCH, of Newton, in the county of Middlesex and State of Massachusetts, have invented certain new and useful Improvements in Staking-Machines, of which the following is a specification.

This invention has for its object to provide an improved "staking-machine," so called, adapted to secure watch-movement wheels to pinion-staffs; and it consists in the improvements which I will now proceed to describe and claim, reference being had to the accompanying drawings, of which—

Figure 1 represents a front elevation of a staking-machine embodying my improvements. Fig. 2 represents a side elevation of the same. Fig. 3 represents a vertical transverse section on the line 3 3, Fig. 1. Fig. 4 represents a section on line 4 4, Fig. 2. Fig. 5 represents a section on line 5 5, Fig. 1. Fig. 6 represents a section on line 6 6, Fig. 3. Figs. 7, 8, and 9 represent enlarged sectional views of the portions of the machine which perform diversely on the work, different relative positions assumed being shown in different views. Fig. 10 shows an enlarged section of parts appearing in Fig. 3 between dotted lines 7 7.

The same letters of reference indicate the same parts in all the figures.

In the drawings, *a* designates a stationary cylinder provided with pistons *b* *c* which are normally held central of the cylinder by springs *d* *e*, the spring *d* being somewhat lighter than the spring *e*, for a purpose hereinafter explained.

To the upper piston *b* is suitably secured a sleeve or hollow rod *f* extending through the cylinder and engaging the end of a lever *g* pivoted at *h* to a standard *i* formed upon the cylinder-head *k*. The outer end of said lever *g* engages a plunger *l* fitted to move longitudinally in a sleeve *m* secured to the cylinder.

The lower piston *c* is secured to a rod *n* having an enlarged portion *o* upon which the under side of said piston rests, while the smaller portion of the rod extends upwardly into the sleeve or rod *f*, the arrangement being such that the pistons are centrally guided in the cylinder and prevented from binding therein.

The lower end *o* of piston-rod *n* rests upon an arm *p* pivoted at *p'* to a block *q*. (See Fig. 6.) Said block is adjustably secured in a recess *r* formed in a downwardly-projecting portion of the cylinder. A screw *s* engages the upper portion *t* of the block *q* and is operated by a hand-wheel *u* to adjust the arm *p* for a purpose pointed out hereinafter. The free end of the arm *p* rests upon a lever *v* pivoted at *w* to a standard *y* formed upon the under side of the cylinder. The outer end of said lever bears upon a plunger *a'* incased in a sleeve *b'* and is adapted to be moved longitudinally by said lever *v*, which is so arranged as to be moved independently of the piston *c* by the operator through a rod *c'* attached thereto and a treadle *d'* attached to the rod *c'*.

The pistons are moved in the cylinder preferably by means of compressed air which enters the cylinder from a supply-pipe *e'* through a passage or port *f'* formed in the cylinder-shell, the opening of said passage being midway of the pistons, Fig. 4, so that the pistons may be moved in opposite directions to operate the levers *v* *g* and their adjuncts.

The entrance of the air to the cylinder is controlled by a valve *g'* of any suitable construction. The one here shown is piston-shaped and fitted to slide in a bushing *h'*, secured in a projection *i'*, formed on the cylinder *a*. Said valve is provided with a passage *j'* and has a recess *k'* formed in one end, and in the shell surrounding said recess is formed a port *l'*, Fig. 5, adapted to register with the passage *f'* when the valve is moved to permit of the same, the arrangement being such that the port and recess form an exhaust-opening 90 for the air when it has performed its work.

The position of the valve *g'* shown in Fig. 5 is such that the passage *j'* formed therethrough registers with the passage *f'* to admit the air to the cylinder, but the normal position of the valve is in the position just described, in which the exhaust-opening *l'* registers with the passage *f'*, being held in said position by a spring *m'*, one end of which bears upon a bracket *n'* attached to the under side of the cylinder *a*, while the other end bears against a collar *o'* secured to a rod *p'*, which rod is secured to the valve *g'* at one end, the other end passing through the bracket *n'* and

having a knob or "pult" q' attached thereto. (See Fig. 2.)

- The lever g engages at its outer end with a cap r' fitted upon the plunger l , which has an enlarged portion s' closely fitting the sleeve m and adapted to slide therein. The lower portion t' of the plunger is reduced in diameter and is surrounded by a sleeve u' , the upper end of which bears against a spring v' , Fig. 10, the upper end of which rests against a collar w' loosely surrounding the reduced portion of the plunger l , the sleeve being held in position vertically by a pin y' , secured to the plunger l , and projecting through a slot a^2 in the sleeve m , as will be more clearly understood by reference to Fig. 10. A spring b^2 has one end bearing against the enlarged portion s' of the plunger l and the other resting upon a sleeve c^2 , the lower end of which bears upon a head d^2 secured to the sleeve u' , the arrangement being such that when the plunger is operated downwardly a differential yielding pressure is applied, the purpose of which will be explained later in the operation.
- 25 The plunger l is bored to receive a "set" or "staker" e^2 , preferably formed in sections to prevent binding or springing in the bore, as would be the case were one piece used. The upper end of the bore is screw-threaded 30 and a screw f^2 inserted therein, the lower end of which bears against the upper end of the staker or set e^2 , providing means of adjustment for the latter and holding it in position against pressure.
- 35 The arm p is adjustable upon the lever v in the direction of its length by means of the screw s' and block q , so that the degree of pressure exerted by the piston c upon said lever may be varied to suit different classes 40 of work; and to accurately adjust the leverage I have provided an indicator h^2 , which is attached to the sliding block q , as shown in Fig. 6, the outer end registering with a scale i^2 upon the outside of the machine.
- 45 An adjusting-screw j^2 is also shown to limit the downward movement of lever v , and the latter at its outer or shorter end bears against a cap k^2 , the upper portion of which has a socket which receives the lower end of plunger a' , adapted to move vertically in a bushing l^2 , fitted to the lower portion of socket b' . The upper portion of said plunger is reduced in diameter and is surrounded by a spiral spring m^2 , the lower end of which bears against 55 the enlarged portion of the plunger, and the upper end bears against the upper end of the socket. The object of said spring is to normally sustain the lever v and arm p in contact with the lower end of the rod o by means 60 of pressure exerted upon the plunger a' , as will be readily understood by reference to Fig. 3. The plunger a' is also provided with a set n^2 in the same manner as the plunger s' , the upper end o^2 of which projects above said plunger, Fig. 3, which is surrounded by a bushing o^3 , to which bushing is fitted a cap o^4 , having a central opening o^5 corresponding

to the conical end of the set o^2 . Said cap is also fitted with a depression or counterbore o^6 to receive a wheel o^6 of a watch for the purpose of inserting the staff into the same.

The ends of the sets are provided with sockets o^9 o^{10} for the reception of the staff of the pinion o^8 during the operation.

Operation: The operator depresses the treadle and draws down the longer end of the lever v , which raises the shorter end of said lever and with it the plunger a' until the conical end of the set engages the opening o^5 in the cap o^4 , as shown in Fig. 7. A pinion o^8 is placed thereon, and on pressure from the treadle being removed the plunger resumes its normal position, as shown in Fig. 8, with the pinion resting thereon. A wheel o^6 is then placed upon the cap o^4 , and air is admitted 85 into the cylinder by the operation of the valve already described, and the piston b is moved upwardly, which movement, through the lever g , depresses the plunger l until the head d^2 rests upon the wheel, as shown in the last- 90 mentioned figure. During the movement of piston b the piston c has remained inoperative by reason of the varying resiliency of the springs d and e , the spring d yielding to the pressure sufficiently to complete the movement of piston b before the yielding of spring e . The movement of piston b being completed, as before explained, with the result shown in Fig. 8, the movement of piston c now 100 takes place in a downward direction, depressing arm p and lever v , thereby raising plunger a' , with the pinion resting thereon, into the position shown in Fig. 9, in which position the projecting portion o^7 of the staff is forced into the center of the wheel, the head d^2 yielding against the pressure of the springs v' and b^2 to permit the set e^2 to press directly upon the staff and upset the same within the wheel.

What I claim as my invention is as follows:

1. In a machine of the character described, the combination of opposed plungers; mechanisms for advancing the same toward each other, said mechanisms actuated by an agent common to both; and restraining means, that applied to one of said mechanisms being inferior to that applied to the other, whereby one plunger is caused to advance before the other, although impelled by the same agent.
2. In a machine of the character described, the combination of opposed plungers, a cylinder, a pair of pistons therein, means for admitting fluid under pressure between said pistons, and movement-reversing connections between the pistons and plungers respectively, whereby movement of the pistons away 120 from each other advances the plungers toward each other, the plungers moving in an opposite direction to their respective pistons, substantially as described.
3. In a machine of the character described, the combination of a cylinder, a pair of pistons therein, means for admitting fluid under pressure between said pistons, springs resisting movement of said pistons by the fluid

130

pressure, opposed plungers to act on the work, and suitable connections between the said plungers and the pistons.

4. In a machine of the character described, the combination of a cylinder, a pair of pistons in said cylinder, springs holding said pistons in the middle of the cylinder, the spring applied to one piston being stronger than that applied to the other, opposed plungers for acting on the work, and suitable connections between the plungers and the pistons.

5. In a machine of the character described, the combination of opposed plungers to act on the work; and mechanism to advance the said plungers respectively and both actuated by a common agent, one of said mechanisms including a disconnected lever which while serving to transmit power from the said common agent to one plunger may be independently operated to advance that plunger, substantially as described.

6. In a machine of the character described, the combination of a plunger for supporting the work, a lever engaged with said plunger, a second lever engaged with but disconnected

from said first lever and pivoted to a movable support, means for adjusting said support to vary the point of engagement of the two levers, and means applied to the second lever 30 for impelling it against the first lever and thereby operating the plunger and a cooperating plunger and its actuating mechanism.

7. In a machine of the character described, the combination of an upper plunger, a head 35 surrounding the same, a yielding connection between said head and plunger, a lower plunger, an anvil with provision for receiving the latter, and means for actuating the plungers, with provisions for movement of the upper 40 plunger with its surrounding head in advance of the lower plunger, for the purpose described.

In testimony whereof I have signed my name to this specification, in the presence of 45 two subscribing witnesses, this 5th day of July, A. D. 1895.
